(57) **CLAIM**

The ornamental design for a rolling cat toy, as shown and described.

DESCRIPTION

FIG. 1 is a front elevational view of a rolling cat toy showing my new design;

FIG. 2 is a rear elevational view thereof;

FIG. 3 is a top plan view thereof;

FIG. 4 is a bottom plan view thereof;

FIG. 5 is a left side view thereof;

FIG. 6 is a right side view thereof;

FIG. 7 is a bottom, front and right side perspective view thereof;

FIG. 8 is an enlarge view of portion 8 in FIG. 7; and,

FIG. 9 is a bottom, front and right side perspective view showing the rolling cat toy in a use state.

The broken lines in the drawings illustrate portions of the rolling cat toy which form no part of the claimed design. The broken lines depicting the rope attached to the rolling cat toy in FIG. 9 also form no part of the claimed design.
